PACKING MACHINERY

Walter Everett Molins, Deptford, London,
EnglandApplication June 6, 1931, Serial No. 542,617, and
in Great Britain June 7, 1930

5 Claims. (Cl. 226—5)

This invention relates to cigarette packing machines, and has for its object to provide means whereby cigarettes may be located with their printed matter all facing in one direction and face upwards so that they may be packed in this manner, and thereby enhance the appearance of the finished package.

It should be explained that cigarettes always have the printed matter located in a definite position with respect to the seam and generally the printing is on the opposite side to the seam.

The invention comprises a cigarette turning device for use on packing machines comprising means for rotating the cigarettes about their axes, and means for arresting the rotation of the cigarettes when the same are disposed in a predetermined position.

The invention will be more particularly described with reference to the accompanying drawings, in which:—

Fig. 1 is a section of a portion of a cigarette feeding apparatus with one form of the invention applied thereto.

Fig. 2 is a plan view of Fig. 1.

Fig. 3 is a view of the right-hand corner of Fig. 2 showing certain details omitted from that figure.

Fig. 4 is a section of Fig. 2 on line 4—4.

Fig. 5 is a section of Fig. 2 on line 5—5.

Fig. 6 is a view of a portion of Fig. 2 taken in the direction of the arrow 6.

Fig. 7 is an enlarged section of a cigarette.

Fig. 8 is a diagram of a device for turning over oval cigarettes.

Fig. 9 is a diagram of an alternative device for turning over oval cigarettes.

Fig. 10 is a diagram illustrating a modified form of the invention.

Fig. 11 is an elevation in diagrammatic form of a further modification, and

Fig. 12 is a plan of Fig. 11.

Referring to Figs. 1 to 7, the cigarettes are placed in a hopper (not shown), and fall down the slots between a number of vanes 1 on to a plate 2. This plate is furnished with a number of curved grooves which locate the cigarettes in position. The cigarettes are fed out in rows from beneath the vanes by pusher pieces 3 carried on a chain conveyor 7 and the cigarettes pass beneath a brush 2^a and a plate 2^b having grooves corresponding to those in the plate 2 (see Fig. 5). The cigarettes are delivered on to a series of rollers 8 which are preferably knurled. The rollers are mounted in bearings formed in a horizontal frame 9 parallel to one another and separated

so that they are free to rotate in the same direction when driven in the manner hereinafter described.

The cigarettes 10 are delivered on to the rollers 8 as shown in Fig. 2 so that the longer axis of each cigarette lies centrally disposed between an adjacent pair of rollers.

The rollers are then rotated for about two revolutions by means of intermittent gearing. A small blade 11 which is preferably a piece of 65 spring steel provided with a sharp end is arranged so that it lies approximately tangential with respect to the periphery of each cigarette (see Fig. 6), and as the cigarettes rotate, the seams, which are formed as shown in Fig. 7, 70 eventually come into contact with the extreme points of the blades and each cigarette is instantly arrested although the rollers may continue to rotate.

In order to prevent the cigarettes from coming 75 into contact with the pointed blades 11 before they are in the required position on the rollers, a movable guide 12, suitably grooved to correspond with the groove in plates 2 and 2^b, over which the cigarettes are fed, is arranged in front of the entry to the rollers, and the guide is raised sufficiently to enable the cigarettes to clear the blades as they pass on to the roller.

In Fig. 1 the guide 12 is carried on an arm 85 pivoted at 13 and operated by a cam 14. A movable stop 15 is also arranged to receive the leading ends of the cigarettes and locate them in position, and in the present case the stop 15 is carried on an extension of the arm carrying the guide 12. As soon as the cigarettes are in the required position, the guide 12 drops, and the cigarettes fall into contact with the rollers 8, as previously mentioned; the weight of the cigarettes depressing the spring blades 11 to a very slight extent. The rollers have worm wheels 16 formed on the ends thereof which engage with a worm 17. The worm 17 has a small gear 18 on the end thereof which is rotated by a large gear 19. The gear 19 is integral with a ratchet wheel 20 (see Fig. 3), the latter being intermittently rotated by a pawl 21 driven by a link 22 connected to the cam disc 14 which is continuously rotated. The disc 14 is fixed to a spindle carried in a bearing 23 and driven by a sprocket wheel (not shown). After the rollers have rotated twice, all the cigarettes will be found to lie in the required position, and they are then transferred by the pusher piece 24 of a conveyor 25 on to a plate 26 being controlled in transit by 100 guides 9^a (Fig. 4).

The pusher piece 24 is controlled by a fixed trip 24^a, Fig. 1, to cause it to rotate clockwise about its pivot and avoid the cigarettes deposited on the plate 26. The cigarettes are removed 5 for insertion into the packets by a conveyor (not shown).

During this movement the cigarettes pass beneath the plate 27 having guides 28 which prevent the cigarettes from being displaced.

10 In the case of non-circular cigarettes, for example, oval cigarettes, the devices shown in Figs. 8 and 9 may be used in order that the periphery of the cigarette shall move into contact with the point of the blade throughout the revolution of the cigarette, and in order to effect this, a plate 29 may be provided as shown in Fig. 8 which forms a flat surface over which the cigarette can ride, thus ensuring that the periphery is always definitely in contact with the blade 20 point in spite of the shape of the cigarette.

In Fig. 9 the rollers are separated somewhat widely so that they will just support an oval cigarette when it is lying flat and a third roller 30 is interposed as shown which supports the 25 oval cigarette when it is standing on the longer axis of the oval.

As an alternative, the blade may be given any required movement in order to enable it to conform with the periphery of a non-circular cigarette when the same is being caused to rotate 30 by the rollers, but generally speaking, the apparatus shown in Figs. 1 and 2 will handle all common shapes of oval cigarettes, and the modifications mentioned above would only be required 35 for abnormal shapes.

Referring to Fig. 10, this shows diagrammatically a further method of carrying out the invention. The cigarettes are delivered by any suitable mechanism to an intermittently moved 40 band 31 which, at the moment of delivery, is stationary. The band is then moved a short distance in the direction of the arrow, and the friction of the band is sufficient to cause the cigarettes to rotate until they are arrested by the 45 blades 32. Guides 33 prevent the cigarettes from moving bodily along the band. After the cigarettes have been rotated to the required position, the band comes to rest again and the cigarettes are removed to the packing machine.

50 Referring to Figs. 11 and 12 which show diagrammatically a further way of carrying the invention into effect, the cigarettes are delivered from the vanes 34 by a plunger 35 on to a flat bristle brush 36. The brush is one of a series 55 carried on a chain conveyor 37 intermittently moved in the direction of the arrow. The brush is at rest at the moment the cigarettes are delivered on to it and is temporarily inclined so that the cigarettes tend to roll towards the needle 60 points 38.

In order to give the brush this temporary inclination, it is attached to the chain conveyor by side plates 39, the front plate shown in Fig. 11 65 of the drawings being slotted to permit the brush to tilt as the plate moves over a cam 40.

When the cigarettes are in position on the brush the latter is given a rapid vibration by means of a rotary striker 41, the plates 39 being 70 of spring steel to permit the brush to vibrate without disturbance of the chain conveyor which moves in guides 42. The bristles of the brush are all inclined at the same angle to the horizontal and the result of the vibration is to cause the cigarettes 75 to rotate by the frictional ratchet action

of the inclined bristles upon the surface of the cigarettes.

After a short time, the vibration ceases, the cigarettes having rotated to the required position and the conveyor moves on one stage so that the brush 36 delivers the cigarettes to a grooved plate 43 from which they may be taken to the packing machine.

The brush 36 is provided with a pusher 44 which transfers the cigarettes on to the plate 85 and the top of the pusher is slotted to form small projections which pass through corresponding slots 45 in a plate 43.

Numerous other methods of carrying out the invention will be apparent, for example, cigarettes may be delivered on to a horizontal plate 90 carried on springs into contact with blades or the like, and the plate may be given a vibratory movement similar to that used on "jigger" conveyors in order to cause the cigarettes to rotate 95 in the required direction.

What I claim as my invention and desire to secure by Letters Patent is:—

1. A cigarette turning device for use on packing machines comprising a series of rotatable 100 parallel rollers operable to move the cigarettes about their longitudinal axes, and means for engaging the seams of the cigarettes thus moved to arrest the movement, said means being positioned beneath the upper surface of said rollers. 105

2. In apparatus for use with cigarette packing machines, the combination with means for feeding cigarettes through a predetermined path in the direction of the longitudinal axes thereof, of means located adjacent the path of movement of 110 the cigarettes and movable transversely thereof for rotating the cigarettes about their longitudinal axes, and means for arresting rotational movement of the cigarettes when the latter reach a predetermined position, said last named means 115 being located beneath the cigarettes.

3. In apparatus for use with cigarette packing machines, the combination with a continuous conveyor for feeding round cigarettes in the direction of their longitudinal axes into predetermined 120 positions of rest, of a continuous conveyor for thereafter removing the cigarettes from the positions of rest, and means for engaging and rotating the cigarettes occupying such positions of rest through variable angles determined by the 125 initial rotational positions of the cigarettes.

4. A cigarette turning device for oval cigarettes comprising a plurality of parallel rollers, means for feeding a cigarette onto and between adjacent rollers, means for rotating said rollers to rotate 130 the cigarette, an abutment beneath the cigarette for engaging the seam thereof to terminate rotation of the cigarette when the latter reaches a predetermined rotational position, and means occupying a fixed position and engaging the lower surface of the cigarette to support the latter in cooperative relationship with said abutment regardless of the rotational position of the cigarette. 135

5. A cigarette turning device comprising a plurality of parallel rollers, means for feeding a cigarette onto and between adjacent rollers, means for rotating said rollers to rotate the cigarette, and means for terminating rotation of the cigarette when the latter reaches a predetermined rotational position, said last named means comprising an abutment positioned beneath the cigarette for engagement by the cigarette seam. 140 145
